(57) CLAIM

The ornamental design for a body support pillow, as shown and described.

DESCRIPTION

FIG. 1 is a front elevational view of the body support pillow of the present invention;

FIG. 2 is a rear elevational view of the body support pillow of FIG. 1;

FIG. 3 is a right side elevational view of the body support pillow of FIG. 1;

FIG. 4 is a left side elevational view of the body support pillow of FIG. 1;

FIG. 5 is a top plan view of the body support pillow of FIG. 1, the bottom plan view being a mirror image thereof;

FIG. 6 is a top, front, right side perspective view of the body support pillow of FIG. 1; and,

FIG. 7 is a rear perspective view in an alternate position (bent).
